UNITED STATES PATENT OFFICE

MARY CESARIO, OF KENOSHA, WISCONSIN

MOP WRINGER

Application filed August 25, 1932. Serial No. 630,463.

This invention relates to mop wringers, and has particular reference to that type of mop wringer comprising a bucket or a receptacle together with wringing rolls mounted in operative position thereon and between which the swathe of the mop is passed for forcing the water from the swathe into the bucket or receptacle; and a salient feature of the present invention is the provision of a 5 mop wringer wherein the bucket or receptacle is provided with two compartments, one for clean water and the other for the dirty water wrung from the mop, together with a novel form of wringer associated with 10 the receptacle or pail, the entire device consisting of but relatively few parts, and being capable of easy manipulation and ready 15 transportation from one place to another.

The invention, together with its numerous 20 objects and advantages, will be best understood from a study of the following description taken in connection with the accompanying drawings wherein:

Figure 1 is a side elevational view of the 25 wringer.

Figure 2 is a front elevational view thereof with certain parts broken away and shown in section.

With reference more in detail to the drawings it will be seen that the improved wringer 30 comprises a pail or receptacle generally designated by the reference character 5. The receptacle in the present instance is of general rectangular configuration and is provided 35 with two compartments, of which one, the compartment 6, is for water squeezed from the mop, and the other, the compartment 7, is for clean water. The compartments 6 and 7 are formed through the medium of a vertical 40 partition 8 supported between the side walls 9 of the bucket or receptacle 5.

The receptacle 5 is mounted on swivelled 45 casters 10, the casters 10 being located one each at the corners of the bottom of the receptacle 5.

The receptacle 5 is also provided with suitable 50 brake means adjacent opposite ends thereof, and each of said brake means includes a bar 11 secured at one end to an end wall 12 of the receptacle, and having a free

end projecting forwardly and said free end having pivoted thereto a ground-engaging stop including a shank 13 provided on its lower end with a knob 14 of rubber or other suitable yieldable material to frictionally engage the ground and thereby retain the receptacle 5 against casual movement.

Mounted on the receptacle 5 is a wringer per se designated generally by the reference character 15. Wringer 15 comprises a pair of elongated parallel bars 16 which are secured at their lower ends to the partition 8 through the medium of rivets or other fastening elements 17. For the major portions of their lengths, bars 16 are spaced, and at their upper ends converge and are secured together as at 18. Rising from that end wall 12 of the bucket 5 forming one of the walls of the compartment 6 is a standard 19 and supported between the standard 19 and the bars 16 is a wringer roll 20, the latter being disposed adjacent the upper ends of the standard 19. A substantially U-shaped frame includes curved side or arm portions 21 pivoted intermediate their ends as at 22 to the standard 19 and one of the bars 16. The end portion of the referred to frame is designated by the reference character 23 and has rotatably mounted thereon a roller 24 cooperable with the roller 20 for squeezing the swathe of the mop therebetween for forcing the water from said swathe.

At their free ends, the arms or sides 21 of the aforementioned U-shaped frame are provided with eyes 25 with which are engaged pintles 26 provided on the free ends of the sides or arms 27 of a substantially V-shaped bracket that extends downwardly from the arms 21 at the front of the receptacle 5. At the apex thereof, the V-shaped bracket referred to supports a foot pedal 28. The arms 27 of said bracket are of resilient material and can be readily swung inwardly towards one another for moving the pintles 26 out of engagement with the eyes 25.

The aforementioned U-shaped bracket including the parts 21 and 23 is normally urged to rotate in an anti-clockwise direction through the medium of a spring 29 connected at one end with one of the arms 21, and at its

upper end with the upper edge of an end wall 12 as shown in Figure 1, whereby roller 24 is normally retained away from the roller 20.

- 5 For rotating the roller 20 there is provided a shaft 30 mounted in a manner hereinafter made manifest adjacent the upper ends of the bars or standards 16, and this shaft 30 has a chain and sprocket connection 31 with that 10 end of the roller shaft 20 supported between the bars 16 as shown in Figure 2. Shaft 30 is provided on one end with a crank handle 32. Obviously, by rotating the shaft 30, the roller 20 will be rotated.
- 15 For supporting the shaft 30 there is provided a pair of bearings 33 within which the shaft 30 is journaled. These bearings 33 are provided on the ends of short straps 34 provided with pins 35 adapted to be engaged 20 with selected openings 36 provided in the upper portions of the bars 16. It will be noted that each of the bars 16 is provided with a vertical series of spaced openings 36 and in alignment with the series of openings 25 36, said bars are also provided with vertical slots 37 for accommodating the shaft 30. It will thus be seen that by placing the pins 35 in the desired apertures 36 the shaft 30 may be mounted at the desired elevation for 30 taking up slack in the chain 31.

There is also provided for each of the compartments 6 and 7 drain cocks 38.

The use of the device is thought apparent. The clean water in compartment 7 may be 35 used for scrubbing purposes, and when it is desired to wring the mop, the swathe thereof is placed between the rollers 20 and 24 and by pressing on the pedal 28, roller 24 is 40 moved into cooperative position with the roller 20 for squeezing the swathe of the mop therebetween. With the swathe of the mop thus arranged between the rollers 20 and 24, roller 20 may be rotated by rotating shaft 30, 45 power being transmitted from the shaft 30 through the chain and sprocket mechanism 31 to the roller 20 as is apparent.

Even though I have herein shown and described the preferred embodiment of the invention, it is to be understood that the invention is susceptible of further changes, 50 modifications, and improvements coming within the scope of the appended claim.

What is claimed is:

55 A mop wringer comprising in combination a receptacle provided with two compartments, swivel casters supporting said receptacle, laterally extending bars mounted on the receptacle at relatively opposite ends thereof, and ground engaging elements pivotally connected with said bars; and a wringer device 60 mounted on said receptacle in operative position to one of said compartments, said wringer device comprising a pair of spaced parallel supports, a roller rotatably supported between said supports, a shaft mounted 65

on one of said supports above said roller, chain and sprocket means connecting said shaft with said roller, handle means for said shaft, a curved arm pivoted to each of said supports intermediate the ends of said arm, a roller supported between said arms at one end of said arms, a foot pedal supporting bracket pivotally connected with the other end of said arms, and yieldable means urging said arms to rotate in one direction for normally retaining said rollers spaced apart.

70 In testimony whereof I affix my signature.
MARY CESARIO.
